By *June Daniels*
Attorney.

UNITED STATES PATENT OFFICE.

OSKAR JUNGHANS, DECEASED, LATE OF SCHRAMBERG, GERMANY, BY SIEGFRIED JUNGHANS, ADMINISTRATOR, OF VILLINGEN, BADEN, GERMANY.

MECHANICAL TIME FUSE.

Application filed January 12, 1928, Serial No. 246,358, and in Germany January 19, 1927.

The present invention relates to mechanical time fuses adapted to be applied to artillery shells for the purpose of exploding the shell after lapse of a given time following the firing of the shell from a gun, and the invention more particularly pertains to a fuse of the stated kind wherein a clockwork is provided for driving a timing disk upon the firing of the shot, and the timing or setting disk is normally locked and prevented to rotate until released through the shock imparted to the projectile when the shot is fired.

According to this invention the mechanical means employed for the locking and releasing the timing disk are extremely simple and compact in construction efficient and reliable in operation and highly practical. Generally speaking, the invention comprises a lug or tongue cut from the timing disk and bent out of the plane of the disk to form a catch engaging a pin provided in the usual fuse cap, and further a hammer constructed and arranged in a manner that, upon the firing of the projectile, the said hammer will act by its weight, owing to the shock received, to bend back the said catch and to thereby release the timing disk from its locked engagement with the pin, so that the clockwork can start to rotate the disk.

It will be seen that a mechanism of this kind is not only very simple and efficient, but also absolutely reliable inasmuch as exactly at the moment of firing the shot the locked parts will be released with certainty, so that the clockwork will start immediately upon the firing of the shot and the shell will explode accurately at the desired distance, or the exact moment to which the timing disk has been previously set.

Proceeding to a detailed description, reference is had to the following specification and drawings in which there is exhibited one example or embodiment of the invention which is in no way intended as a limitation upon the scope of the appended claims as it is to be clearly understood that variations and modifications which fairly fall within the

true scope of said claims, may be resorted to when found expedient.

In the accompanying drawings forming a part of this specification and wherein like characters designate like parts in the several views:

Figure 1 is a view in longitudinal section of the fuse and

Figure 2 is a cross-section taken on the line A—B of Figure 1.

The timing or setting disk *a* is fixed to the main spindle *b* of the clockwork of the fuse in the usual manner. A tongue *c* is cut in the disk *a* and bent out of the plane of the latter to form a lug or catch which is slotted at its free end to form a fork engaging over the pin *e* rigidly connected with the cap *d* of the fuse. Firmly attached to the inner face of the top of the cap *d* is a plate-spring *f* which carries a weight at its free end shaped to form a hammer *h*. The spring *f* is secured to the cap by means of screws *g* and the weight or hammer *h* is secured to the spring by riveting or soldering. As will be seen the hammer is suspended to normally occupy a position over and above the tongue or lug *c* projecting from the timing disk *a*.

The operation is as follows:

Due to the shock imparted to the projectile at the firing moment the hammer *h* will rebound and hit the lug *c* so that the latter will be bent back into the plane of the disk or at least sufficiently far to be out of engagement with the pin *e*. At the very moment this occurs and the timing disk thus is unlocked the clockwork will automatically start immediately on the firing of the projectile.

What is claimed is:—

1. A mechanical time fuse of the character set forth, comprising a clockwork, a cap enclosing said clockwork, a timing or setting disk operatively connected with the main arbor of the said clockwork, a lug projecting from the plane of the said timing disk, a pin in the cap co-operating with the said lug to lock the timing disk, and a hammer adapted to bring, upon the firing of

the shot, the said lug out of locking engagement with the pin.

2. A mechanical time fuse as claimed in claim 1, wherein the lug is shaped to form a forked tongue cut and bent out of the metal of the timing disk and adapted to be bent back towards or into the plane of the disk by the impact of the hammer.

3. A mechanical time fuse as claimed in

claim 1, wherein the hammer is suspended to 10 the one end of a spring the other end of which is firmly attached to the cap.

In testimony whereof I, the said administrator SIEGFRIED JUNGHANS, affix my signature.

SIEGFRIED JUNGHANS,
Administrator of Oskar Junghans, De-ceased.
